UNITED STATES PATENT OFFICE.

JOHN C. GOOLD, OF ALBANY, NEW YORK.

DESIGN FOR SLEIGH-BODIES.

Specification forming part of Design No. 6,268, dated November 19, 1872.

To all whom it may concern:

Be it known that I, JOHN C. GOOLD, of Albany, county of Albany, State of New York, have invented a Design for Barouche Sleigh-Bodies, of which the following is a specification:

The nature of my design is fully represented in the accompanying illustration, to which reference is made.

In a body of a barouche-sleigh I retain the lower sweep-line of the body, and also the lines of the rear portion of the sleigh as they have been formed in the past in this class of sleighs, and I also retain about the same curve in the line from the driver's seat to the goose-neck in front, excepting I continue the line *a* with a flat curve from the usual full curve *a'* up to a point about on a plane with the point of juncture of the goose-neck with the rocker *B*, as shown. I also extend the usual curved line *b'* from the usual point of its intersection with the upper line *c'* of the front passenger-seat *C* up past with a curving sweep-line, *b*, to a point on a plane with the dotted line *x*, above which the driver's seat is placed, which new line *b* will, with its curve, fall gracefully in with the usual curved line *b'*, as shown, while the upper terminating points of the said lines *a* and *b* will be about fifteen or sixteen inches apart, and about on a plane with the jointure of the goose-neck with the rocker, as at *B*. I also form the upper line *c'* of the sides of the seat *C* straight and on the same plane throughout, as shown; and at the intersection of the said straight line *c'* with the curved line *b b'*, and about at a point fifteen inches (when all the parts are in proportion) below the line of the

bottom of the driver's seat *A*, I suffer the back of the passenger seat to commence, and rise to about on a line with the top of the driver's seat, as shown; the said back of the passenger seat being inclined at its top toward the driver's seat, leaving a space of about eight inches between the two backs at their upper edges, which will give ample room for the knobbing on of the front top curtain, and will also permit the driver to set back on his seat without discommodeing the passengers in the body of the sleigh.

It is to be understood that my design relates to the outline form of the several parts, as set forth, which gives the profile of those parts, and not to any molding, beadings, carvings, or other ornamentation, any of which may be added as taste or fancy might suggest.

A barouche sleigh-body, constructed after my design, presents a prettier crest-panel, *E*, and throws up the driver's seat to a greater elevation, (when considered in relation with the other parts of the sleigh,) and gives to the rear portion, to be occupied by the passengers, a more exclusive appearance, while it also permits the front curtain of the top to appear to effect a separation more remote of the passenger-seat portion from the driver's seat, and renders the whole more graceful in form and tasteful in appearance.

What I claim, and desire to secure by Letters Patent, is—

The design for barouche sleigh-bodies, substantially as herein shown and described.

JOHN C. GOOLD.
